(57) **CLAIM**

The ornamental design for a multiple beverage holder with attachment features, as shown and described.

DESCRIPTION

FIG. 1 is an isometric front perspective view of a multiple beverage holder with attachment features showing my new design;

FIG. 2 is a side elevation view thereof;

FIG. 3 is a side elevation view thereof, showing the side opposite that of the beverage holder in FIG. 2;

FIG. 4 is a front end view thereof;

FIG. 5 is a rear end view thereof, showing the end opposite that of the beverage holder in FIG. 4;

FIG. 6 is a top elevational view thereof;

FIG. 7 is a bottom view thereof; and,

FIG. 8 is a top plan view of a blank for forming the carton of FIG. 1, the bottom plan view being a mirror image thereof. The broken lines in the Figures are for the purpose of illustrating exemplary environmental structure and form no part of the claimed design.
